DESIGN FOR A RECESSED SOAP HOLDER OR SIMILAR ARTICLE

Gustave A. Hallenscheid, Los Angeles, Calif.

Application November 13, 1939, Serial No. 88,222

Term of patent 14 years

To all whom it may concern:

Be it known that I, Gustave A. Hallenscheid, a citizen of the United States, residing at Los Angeles, county of Los Angeles, State of California, have invented a new, original, and ornamental Design for a Recessed Soap Holder or Similar Article, of which the following is a specification, reference being had to the accompanying drawing, forming a part thereof.

Fig. 1 is a perspective view of a soap holder showing my new design.

Fig. 2 is a top plan view.

Fig. 3 is a side elevational view thereof.

I claim:

The ornamental design for a recessed soap holder or similar article, substantially as shown.

GUSTAVE A. HALLENSCHEID.
